UNITED STATES PATENT OFFICE.

CHARLES ED. HAVILAND, OF LIMOGES, FRANCE.

DESIGN FOR DISHES FOR TABLE-SERVICE.

SPECIFICATION forming part of Design No. 16,452, dated January 5, 1886.

Application filed October 5, 1883 Serial No. 108,230. Term of patent 14 years.

To all whom it may concern:

Be it known that I, CHARLES ED. HAVILAND, a citizen of the United States, residing in the city of Limoges, Republic of France, § have invented a certain new and original Design for Dishes Constituting a Table-Service, fully described and represented in the following specification and accompanying drawings, forming a part of the same.

(a) This design is shown in the accompanying fac-similes by thirteen figures, showing its use with various dishes, and illustrating the general application which it may have.

Figures 1 to 8, inclusive, and Fig. 12 exhibit side elevations of the design for the handle as applied to the covers of dishes. Fig. 9 exhibits a perspective view, Figs. 10 and 13 end elevations, and Fig. 11 a top or plan view, of the same. Figs. 1, 4, 7, 8, and 12 exhibit side elevations, Fig. 9 a perspective view, Fig. 10 a front elevation, Fig. 13 an end elevation, and Fig. 11 a plan view, of the design as modified by the combination of handles applied to both the body and cover of the vessels.

The general shape of the handle approximates that of a scallop shell, but may have a contour at the back formed by flutings 2, that terminate at the edge in scallops, (see Fig. 7,) which may be made with more or less curve than is shown, as may be desired.

The handle is an oblong figure, and forms a shallow body with a curved or overhanging top portion, 3. (Best seen in Figs. 9 to 11.) The general shape, as viewed in front, may be more or less circular, and may have some portions formed by lesser arcs than others, as may be seen by comparing the body handles of Figs. 8 and 10. Its overhang may be slight or great, as may be exemplified by comparing the cover handles with the body handles, and this will also vary according to the size of the dish to which it is applied—as, for instance, by a slight overhang in a small dish, or great in a large. Its curvature vertically may vary also, being very slight in small dishes or on covers, or considerable in large dishes, or when applied to the ends or sides of dishes. It may be plain on its exterior, its interior or show flutings, or curved

indentations, and it may have a plain curved lower interior edge, (which is the exposed one,) or be finished with an ornamental scroll, as 4.

In applying this design to the sides or ends of a dish, the single shell-like form shown in Figs. 1, 4, 7, 8, 9, 10, 11, will preferably be adopted; but the duplex shell-like form shown in Figs. 12 and 13 may be used; and, while in its general application to the covers of dishes alone, the duplex shell-like form constitutes the design, said covers may, when combined with dishes, embody a handle of single shell-like form, as is shown in Figs. 12 and 13.

This design may be applied to all dishes of porcelain or earthenware, and may be beautified as taste or fancy suggest or trade considerations require. It may have associated with it other ornamentations, as in the case of the raised vine in Fig. 11, or by the colored 65 ornamentations shown in Figs. 1, 8, and 10.

It is obvious that without departing from the invention the side or end handles may have the duplex form of handle shown on the covers, and that when combined with single shell-like side or end handles the cover handle may be the single shell-like form.

The essential characteristics of this design are, first, the duplex shell-like handle; second, the duplex shell-like handle fluted as described; third, the shell-like central handle of the cover in connection with the shell-like end handles of the dish; fourth, the design for a covered dish having a cover embodying a duplex shell-like handle and a body embodying single shell-like handles.

The following are disclaimed herein for the reason that they are contained in my application filed July 30, 1883, Serial No. 102,353: The design constituted in whole or in part by the trilateral-corner shape configuration or ornamentation; the design constituted in whole or in part by the peculiar shape of the dishes themselves; the design constituted by the peculiar shape of the handles of the bodies of the dishes shown in Figs. 2, 3, and 5, the same being P form in their general configuration.

The following is alone claimed herein:

1. The design for a handle of dishes and

covers, the same consisting of the duplex shell-like form, substantially as shown and described.

2. The design for a handle of dishes and covers, the same consisting of the duplex shell-like form fluted, substantially as shown and described.

3. The design consisting of the combination of the cover having a shell-like central handle with the dish having shell-like handles, substantially as shown and described.

4. The design for covered dishes, the same

consisting of the combination of the cover having the duplex shell-like handle with the dish having single shell-like handles, substantially as shown and described.

In testimony whereof I have hereunto set my hand in the presence of two subscribing witnesses.

CH. ED. HAVILAND.
